UNITED STATES PATENT OFFICE.

JOSEPH H. CONNELLY, OF WHEELING, VIRGINIA.

IMPROVEMENT IN LAMP-WICKS.

Specification forming part of Letters Patent No. 37,276, dated January 6, 1863.

To all whom it may concern:

Be it known that I, JOSEPH H. CONNELLY, of Wheeling, in the county of Ohio and State of Virginia, have invented a new and useful Improvement in Wicks for Lamps; and I do hereby declare the following to be a full, clear, and exact description thereof, reference being had to the annexed drawings, forming part of this specification, in which—

Figure 1 represents a lamp-wick, the upper portion of which is opened to exhibit the mode in which it is constructed. Fig. 2 represents a piece of raw cotton folded in paper to form the inside of my improved wick. Fig. 3 is a strip of raw cotton prepared for insertion in the wick.

In each of the figures like letters of reference denote similar parts of the wick.

My invention consists of certain improvements on the internally-napped lamp-wick invented by John Cook and myself, and for which Letters Patent of the United States were granted to us on the 26th day of August, 1862. That invention, as described in said Letters Patent, consisted in a lamp-wick constructed of canton-flannel or other suitable textile fabric having a napped surface on its inner side when folded so as to form a hollow or tubular wick, or woven double for the same purpose, the object being to afford, by means of the internally-napped surface, a better conductor for the oil or burning-fluid, the capillarity of this internally-napped wick being increased, if desired, by the insertion of a thin layer of raw cotton next to the napped surface. In the specification accompanying the patent referred to the wick is described as being made of pieces of canton-flannel folded in tubular form and sewed together, or of a suitable web woven double. The design of my improvement is to simplify the construction of this improved wick and obviate the necessity of sewing the fabric at all by bringing the raw edges of the strip composing the wick together, and covering the joint with a narrow piece of some thin material pasted or glued thereto; and another object is to improve and increase the capillarity of the internally-napped wick by inserting in the tube or outer casing of canton-flannel or other napped fabric a strip of unsized paper or of raw cotton folded in paper. I also make a tubular wick of any suitable textile fabric not

having a nap, and communicate the requisite degree of capillarity thereto by inserting therein a strip of unsized porous paper or of raw cotton, or cotton and paper combined.

To enable others skilled in the art to make use of my invention, I will proceed to describe it more fully.

The outer portion or casing forming the tube of my improved lamp-wick may be made of any suitable textile fabric, of cotton, linen, or other material, and either having a nap on one side or being devoid of nap on both sides, as may be desired, but woven so closely that the threads will not catch in or be pulled loose by the teeth of the feed-wheel by which the wick is raised or lowered in the lamp. This outer casing or tube, *a*, (see Fig. 1,) is cut into long strips of uniform width, double that of the wick to be made from it. This strip is folded down on each side so that its edges will meet in the center of the wick on one side, as seen in Fig. 1. If the wick is to have a filling of paper or cotton it is now inserted; but if the fabric has a heavy nap the napped side is folded in. A narrow strip of muslin, paper, or other suitable material, *b*, is then pasted over the united edges of the wick throughout the entire length of the strip, and the wick thus formed is then pressed flat. The cutting of the strips of canton-flannel, or other article forming the tube or outer casing of the wick, the insertion of the raw cotton, paper, or other filling, and the folding over of the outer casing, the pasting of the strip of muslin or paper over its united edges, the pressing or flattening of the wick thus formed, and cutting it into pieces of wick of proper length, may all be done very rapidly and at one operation by means of a machine which I have contrived for that purpose. Where the casing or tube *a* of a wick, constructed as just described, is made of canton-flannel, or other article having a nap on one side, it may be desirable to increase its capillarity by inserting in the tube a thin layer of raw cotton next to the napped surface, as described in the specification to the Letters Patent before referred to; but, as my improved wick is not sewed at the edge something is needed to keep the cotton in place and preserve the flat shape of the wick, to effect which I wrap the cotton filling in paper, as seen at *c*, Fig. 2. This paper wrapper *c*, being unsized, aids the capillary

action of the wick, and gives it the requisite stiffness.

Another improvement consists in making the outer casing or tube of the wick of some textile fabric—such as muslin or linen—without any nap on either side, and giving the necessary degree of capillarity by inserting within the tube or casing, made as hereinbefore described, a strip or strips of porous unsized paper, raw cotton, or other article having similar capillary properties. These may be used either together or either of them alone—as, for example, a casing or tube of muslin may be filled with a strip of porous paper, or with a strip of raw cotton folded in paper, or with a strip of stiff paper and a slight layer of cotton on either side of the paper.

The advantages of my improved wick are that it possesses a greater degree of capillarity than the woven cotton wick now generally in use that the outside of the wick, being more closely woven than the ordinary cotton wick, is more easily inserted into the wick-tube of the lamp, and is more readily moved up and down by the feed-wheel.

The paste or cement used to join the edges of the outer casing or tubular part of the wick may be made of flour paste, or starch paste, with which should be mixed a small quantity of gum-arabic or glue. If the material of which the outer casing of the lamp-wick is made is thin enough to permit of the edges being lapped without making the wick too thick in

the middle they may be united with the paste in that way, instead of pasting a thin strip over the united edges.

What I claim as new, and desire to secure by Letters Patent as an improvement on the lamp-wick for which Letters Patent were granted on the 26th August, 1862, to Joseph H. Connally and John Cock, is—

1. Making a hollow wick for lamps of a folded strip of muslin or other textile fabric by uniting the edges of the strip by means of a paste or cement insoluble in the oil or burning-fluid which is to be burned by the wick.

2. Inserting in an internally-napped hollow or tubular lamp-wick a strip or strips of porous paper, or raw cotton wrapped in paper, so as to give to the wick the requisite stiffness and shape while increasing its capillary power.

3. Making hollow or tubular lamp-wicks of muslin, linen, or other suitable textile fabric, without nap, and filled with porous paper, paper-pulp, raw cotton, or other substance possessing the requisite capillary property, substantially in the manner hereinbefore described.

In testimony whereof the said JOSEPH H. CONNELLY hath hereunto set his hand.

JOSEPH H. CONNELLY.
